US0D1013755S

(12) **United States Design Patent** (10) **Patent No.:** **US D1,013,755 S**
(45) **Date of Patent:** **** Feb. 6, 2024**

(54) **CAMERA DEVICE WITH ADJUSTABLE BASE**

(71) Applicant: **Google LLC**, Mountain View, CA (US)

(72) Inventors: **Mark Woolhiser Huang**, San Francisco, CA (US); **Sung Bai**, San Jose, CA (US); **Maj Isabelle Olsson**, Sunnyvale, CA (US); **Albert Lee**, San Francisco, CA (US)

(73) Assignee: **GOOGLE LLC**, Mountain View, CA (US)

(**) Term: **15 Years**

(21) Appl. No.: **29/799,847**

(22) Filed: **Jul. 16, 2021**

(51) LOC (14) Cl. **16-05**

(52) U.S. Cl.

USPC **D16/219**; D16/203

(58) **Field of Classification Search**

USPC D16/200, 202-205, 208, 211, 214, 218, D16/219, 221, 242

CLAIM

The ornamental design for a camera device with adjustable base, as shown and described.

DESCRIPTION

FIG. 1 is a front, right side perspective view of a camera device with adjustable base showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines depict portions of the camera device with adjustable base in which the design is embodied that form no part of the claimed design.

1 Claim, 7 Drawing Sheets
